UNITED STATES PATENT OFFICE.

ROBERT J. WILSON, OF GRAFTON, MASSACHUSETTS, ASSIGNOR TO D. T. DUDLEY & SONS COMPANY, OF WILKINSONVILLE, MASSACHUSETTS, A CORPORATION OF MASSACHUSETTS.

THREAD-RETAINER.

1,360,342.

Specification of Letters Patent. Patented Nov. 30, 1920.

Application filed April 15, 1920. Serial No. 374,015.

To all whom it may concern:

Be it known that I, ROBERT J. WILSON, a citizen of the United States, residing at Grafton, in the county of Worcester and 5 State of Massachusetts, have invented a new and useful Thread-Retainer, of which the following is a specification.

This invention relates to a thread retainer particularly designed for use in a loom 10 shuttle of either the automatic or the hand threading type.

Such devices are more or less commonly used to prevent the thread from escaping from the shuttle eye as it is drawn off of 15 the bobbin. It is the object of my invention to provide a thread retainer of extremely simple construction, which will also be very efficient and reliable in operation. With this general object in view, my invention consists 20 of certain arrangements and combinations of parts which will be hereinafter described and more particularly pointed out in the appended claims.

A preferred form of my invention is 25 shown in the drawing, in which—

Figure 1 is a partial plan view of a shuttle to which my invention has been applied;

Fig. 2 is a side elevation of the parts shown in Fig. 1, and

Fig. 3 is a transverse sectional elevation taken along the line 3—3 in Fig. 1.

Referring to the drawings, I have shown a portion of a shuttle 10, having a thread passage 11 communicating with a threading slot 12 through which the thread may be 35 inserted in a shuttle eye 13. The parts thus far described may be of any usual form, the shuttle herein shown being of the hand threading type. A cylindrical recess 14 is 40 formed transversely of the thread passage 11, and is open at its lower end.

My improved thread retainer is preferably 45 formed as a coil of wire 15 having a hook-like extension 16 at the upper end thereto. The coil 15 fits snugly in the recess 14 and may be inserted therein by screwing the coil along the recess to the position shown in

Fig. 3. In this position the extension 16 is 50 disposed transversely of the thread passage 11, thus preventing the thread from throwing out of the passage.

In certain cases it is desirable to provide a friction in the thread passage, for which purpose I may insert a cylindrical block of felt or similar material 17 within the 55 coil 15.

If the coil 15 fits snugly in the recess 14, displacement of the retainer rarely occurs. If necessary the lower end of the recess 14 may be closed after the retainer has been 60 inserted.

It will be seen that I have provided a thread retainer of extremely simple construction, having no movable parts to get 65 out of order and that the construction is very effective for the purpose intended. It will also be evident that changes and modifications can be made therein within the spirit and scope of my invention, as set forth in the claims, and I do not wish to be otherwise limited to the details herein disclosed, 70 but what I claim is:—

1. In a loom, in combination, a shuttle having a thread passage and a recess extending transversely of said passage, and 75 a thread retainer held in said recess and comprising a coil of wire snugly fitting said recess and a hook-shaped extension thereof disposed transversely of said thread passage.

2. In a loom, in combination, a shuttle 80 having a thread passage and a recess extending transversely of said passage and a thread retainer held in said recess and comprising a coil of wire snugly fitting said recess, a hook-shaped extension thereof disposed transversely of said thread passage, and a friction member held within said coil and projecting into said passage.

3. In a loom, in combination, a shuttle having a thread passage and a recess extending transversely of said passage, and a 90 thread retainer held in said recess and comprising a coil of wire snugly fitting said recess, a hook-shaped extension thereof disposed transversely of said thread passage, 95 and a cylindrical felt block closely fitting within said coil and projecting into said thread passage.

In testimony whereof I have hereunto affixed my signature.

ROBERT J. WILSON.
